UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

SOUND-WAVE TRANSLATING DEVICE.

Application filed October 28, 1922. Serial No. 567,583.

To all whom it may concern:

Be it known that I, JOSEPH SLEPIAN, a citizen of the United States, and a resident of Swissvale, in the county of Allegheny and State of Pennsylvania, have invented a new and useful Improvement in Sound-Wave Translating Devices, of which the following is a specification.

My invention relates to telephone systems and apparatus, having particular relation to an improved sound-wave translating device.

One object of my invention is to provide a translating device of the class described wherein sound waves may be faithfully translated into correspondingly modulated electrical energy without impairing the quality, tone and quantity of the translated energy and without introducing distorting harmonics.

Another object of my invention is to provide a telephone translating apparatus which embodies no moving parts and more especially one wherein the usual vibratory diaphragm is eliminated.

A further object of my invention is to provide a sound-wave translating device which is characterized by its simplicity of design, efficiency of operation and lack of complicated adjustments and which lends itself to inexpensive methods of manufacture, the several parts of which may be easily made by existing automatic machinery and may readily be assembled with a minimum expenditure of time and money.

The ordinary resistor microphone of the carbon-capsule type has certain inherent undesirable characteristics well known to those skilled in the art, as, for instance, a vibratory element which not only tends to introduce distortion but also complicates the structure of the transmitter, and requires adjustment.

According to my invention, I provide an improved sound-wave translating system for accomplishing the desired results just mentioned and others hereinafter set forth in the following description. The translating system embodying my invention is based upon experiments showing that a very fine chain of granules, is extremely sensitive to pressure variations incident, for instance, to the presence of sound waves. The chain of granules may be formed of a number of different materials, as for instance, metallic material or carbon, preferably the latter,

In one embodiment of my invention, a chain is formed between a pair of spaced electrodes, which are energized from a source of energy through a constant-current high-impedance resistance device, either by bringing said electrodes in contact and then separating the same or by establishing electrostatic forces in the space between the electrodes. The potential variations across the ends of the chain correspond to variations in the resistance thereof and may be amplified by a three-electrode repeater device of any well known type.

With these and other objects in view, my invention further consists in the nature, the details of construction and the method of operation hereinafter described and claimed and illustrated in the accompanying drawing, wherein the single figure is a diagrammatic view of circuits and apparatus embodying my invention.

In the illustrated embodiment of my invention shown in the drawing, a pair of spaced relatively movable electrodes 1 and 2 of a translating device 3 are connected, respectively, by conductors 4 and 5, to the terminals of a source 6 of direct-current energy. The electrode 2 comprises a pile 7 of carbon granules, which may be contained in a receptacle 8, while the remaining electrode, which is movable relatively thereto, may be composed of copper. A resistor 9 may be connected in series-circuit relation with the conductor 4 to maintain the current therethrough substantially constant. In practice, it has been found that the energy source may have an electromotive force on the order of 2000 volts and that the resistance of the resistor 9 may be on the order of a megohm.

As previously stated, I have discovered that, when the electrodes 1 and 2 are brought in contact and then slowly separated, an extremely fine line or chain 11 of granules is formed therebetween, the resistance of which is extremely sensitive to sound waves.

When the current traversing the carbon chain 11 is held substantially constant by the resistor 9, the variations in the resistance thereof, which occur in the presence of sound waves, are translated into potential variations having a wave-form similar to that of the sound waves. The potential drop across the electrodes 1 and 2 is thus composed of a constant component, namely,

the so-called "quiet voltage drop" and an alternating component which corresponds to the varying intensity of the sound waves.

The alternating component of voltage just mentioned may be translated into amplified currents of corresponding wave form by impressing the same through conductors 12 and 13 upon the grid and filament elements 14 and 15, respectively, of a three-electrode 10 vacuum tube 16, which includes, in addition, a plate element 17.

A condenser 18, having a negligible impedance to currents of sound-wave frequency, is included in the grid conductor 15 12 and serves to prevent the so-called "quiet voltage drop" across the discharge electrodes from operating to effect a blocking of the tube 16. A grid-leak resistor 19 may be included in a circuit 21 which is connected in 20 shunt relation to the grid 14 and to the filament element 15 in order to control the intensity of the negative charges which are accumulated on the grid 14.

A plate-filament circuit for the tube 16 25 includes a source 22 of direct-current energy and a high-impedance coupling resistor 23. The potential variations, which are established across the coupling resistor 23 following the variations in the resistance of the 30 granular chain 11 in the presence of sound waves, may be impressed, through conductors 24 and 25, upon the input elements of a second amplifying device (not shown) or other circuit arrangement designed for employing such modulated electrical energy.

If a high-voltage source of energy is employed in place of the one shown in the drawing, say a generator having a voltage of several thousand volts, an electrostatic 40 field may be established between the electrodes 1 and 2 upon a breakage of the chain 11, which is sufficient to cause the re-establishment of the chain. Thus, the chain 11 may be reformed upon an interruption 45 thereof without moving the electrodes 1 and 2. The advantage of such arrangement is obvious.

In summarizing the operation of my invention, when a carbon-granule chain 11 is 50 formed between the electrodes 1 and 2 and, when the current therethrough is maintained substantially constant, the effect of sound waves is to vary the resistance of the chain, thereby causing potential variations across the electrodes 1 and 2 which correspond to the wave form of the disturbing sound waves. The potential variations are then 55 impressed upon the input electrodes 14 and 15 of the repeater device 16 and translated into amplified potential variations across the coupling resistor 23 which is included in the plate-filament circuit of the device 16. The latter potential variations may be further 60 amplified or translated into variable currents, as desired.

The extreme sensitiveness of the resistance of the chain of carbon granules in the presence of atmospheric-pressure variations resulting from sound waves is believed to be due, in part, at least, to the relatively high 70 contact resistances between the granules and to the large variations of such contact resistances in response to small variations in the contact pressure. Under this theory, the motion of the air due to sound waves 75 tends to vary the length of the chain, making it alternately shorter and longer, and thereby altering the contact pressure between successive particles.

While I have described my invention as 80 embodied in a particular circuit arrangement having specific values and while I have shown but one embodiment of my invention for the purpose of describing the same and illustrating its principles of operation, it is 85 apparent that various changes and modifications may be made without departing from the spirit of my invention. I desire, therefore, that only such limitations shall be imposed thereon as are demanded by the 90 prior art or indicated in the appended claims.

I claim as my invention:

1. A telephone system comprising an electrical circuit including a source of energy, 95 sound-responsive means for introducing in said circuit a variable component substantially identical in wave form to impressed sound waves, said means comprising a mass of carbon granules, an electrode spaced 100 therefrom and a chain of carbon granules therebetween, and means for rendering the currents in said circuit substantially independent of variations in the resistance of said carbon chain.

2. A telephone system comprising an electric circuit including a source of energy, sound-responsive means for introducing in said circuit a variable component substantially identical in wave form to impressed 110 sound waves, said means comprising a mass of carbon granules, an electrode spaced therefrom and a chain of carbon granules therebetween, and means for rendering the currents in said circuit substantially independent of variations in the resistance of 115 said carbon chain, and means responsive to said variable component for reproducing the impressed sound waves.

3. In combination, a pair of spaced electrodes, a chain of carbon granules therebetween and a source of energy operatively associated with said spaced electrodes, the magnitude of the electric field between said electrodes being sufficient to cause the reforming of said chain upon the breaking of the same.

4. In a telephone system, a circuit including a relatively large, substantially constant-current resistance device, a relatively small 120

- variable-resistance device comprising a pair of spaced electrodes having a chain of carbon granules therebetween, and means for establishing currents in said circuit and for 5 re-establishing said chain upon the breaking of the same.
5. In an electrical system, a circuit including a relatively small variable-resistance device comprising a pair of spaced electrodes 10 and a chain of carbon granules therebetween, a relatively large constant-current resistance device, means operating to establish currents through said chain and to establish electrostatic forces across said pair 15 of electrodes tending to reform said chain upon the chain being broken and energy-amplifying means having its input terminals connected across said chain.
6. An electrical device comprising a fine 20 chain of carbon granules held together by electrostatic forces only.
7. An electrical device comprising a fine chain of granules of a substance having a contact resistance sensitive to variations in 25 the contact pressure, and means for causing said granules to be maintained in chain formation by electrostatic forces.
8. An electrical device comprising a fine 30 chain of granules of a substance having a contact resistance sensitive to variations in the contact pressure, said chain being free from mechanical support intermediate its 35 ends, a source of potential, a circuit including said source and said chain whereby the electrostatic forces between the ends of said 40 chain will hold said chain together, and means for amplifying the variations in an electrical quantity in said circuit resulting from sound impinging upon said chain.
- 40 9. The method of detecting movements in a fluid non-conducting medium which con-
- sists in maintaining, by electrostatic attraction, a chain of granules of a substance having a contact resistance sensitive to variations in the contact pressure and detecting 45 the changes in the chain resistance resulting from said fluid movements.
10. The method of translating sound waves in a fluid medium which consists in maintaining, by electrostatic attraction in 50 said medium, a chain of carbon granules and detecting the changes in the chain resistance resulting from said fluid movements.
11. In a sound-translating device, a chain 55 of conductive particles exposed intermediate its ends to sound waves and means responsive to the changes of an electrical characteristic of said chain for delivering energy corresponding to the sound.
12. The method of producing electrical 60 response to sound, which consists in establishing, near the surface of a mass of loose conducting particles, an electric field sufficient to form a chain of said particles, maintaining across said chain a difference of 65 potential sufficient to keep the chain formed, and subjecting said chain to the sound.
13. In a sound translating device, a mass 70 of loose conductive particles, an electrode outside said mass, a circuit including said mass, said electrode, a source of electromotive force and an impedance, the potential difference created by said source being sufficient to cause a chain of said particles to be established from said mass to said electrode 75 and the magnitude of said impedance being greater than the changes of impedance caused by sound impinging on said chain.
- In testimony whereof, I have hereunto 80 subscribed my name this 25th day of October 1922.

JOSEPH SLEPIAN.
